KYLE

Filed Jan. 9, 1932

UNITED STATES PATENT OFFICE

JOHN GREY, OF NEW YORK, N. Y.

KYLE

Application filed January 9, 1932. Serial No. 585,791.

My invention relates to kyles or wedges, and refers more particularly to a wedge for stretching furs, and the like.

One object of my invention is to provide a kyle comprised of a hinge element, into which several sizes of wedges can be pivoted.

Another object of my invention is to provide a kyle with a flexible hinge element, that when the different sized wedges are positioned therein, the parts will always be in alignment.

A further object of my invention is to provide a kyle with the hinge set off from and away from the highest part of the wedge, preventing material being stretched from getting caught in the hinge.

A still further object of my invention is to provide a kyle with a double concaved, wedge-shaped portion and a hinge element, when positioned, having its convex formation parallel to said concaved portion of the wedge, preventing the marking, ripping or tearing of the material being treated or stretched.

A valuable object of my invention is to provide a kyle with double nail holes in the center and extreme ends of the hinge element to prevent any great strain being placed on the kyle hinge element and bending the same, and to provide a nail hole in the wedge near the hinge and another in the center of the wedge between the concaved portions.

Another valuable object of my invention is to provide a kyle that has rounded portions at points where the kyle comes in contact with the materials, preventing markings on the materials being treated.

I attain these objects preferably by the means illustrated in the accompanying drawing, wherein similar numerals refer to like parts throughout the several views, in which:

Figure 1 is an isometric view of the device in the operating position, illustrating how a piece of fur is stretched by means of the device.

Figure 2 is an isometric view of the device, opened.

Figure 3 is an isometric view of one of the substitute wedges.

Figure 4 is an isometric view of another of the substitute wedges.

Figure 5 is a section taken on line 5—5 of Figure 1, illustrating the concave and convex portions of the device.

Figure 6 is an isometric fragmentary detail of a wedge with a bearing hole therein.

Figure 7 is an isometric view of the hinge element, with pivots therein.

In Figures 1, 2 and 5, the hinge element 1, is comprised of a U-shaped element with nail holes 2 and 3 in one end, and offset bosses containing nail holes 4 and 5, approximately at the center and at the opposite end there are two offset bosses 6 and 7, which contain bearing holes 8 and 9, shown in Figure 5.

The inside edge 10 of this hinge element is convexed at 11, as clearly shown in Figure 5.

These bearing holes 8 and 9 are adapted to receive the pivots 12 and 13, that are in the wedges 14, 15 and 16, each of which wedges is deeper than the other.

Each of these wedges is concaved at 17 and 18, as clearly shown in Figure 5, so that the concave portion is parallel to the convex portion 11, in the hinge element, when the device is shown as being in the closed position, as shown in Figure 1.

The ends of these wedges are rounded at 19, to prevent injury to the materials being stretched, and the wedge is provided with nail holes 20 and 21, for holding the wedge upon some object.

Figures 6 and 7 show an alternative view of the wedge and hinge element, wherein the wedge is provided with bearing holes 22 and 23, that are pivoted in the pivots 24 and 25, that are a part of the hinge element 1.

It is obvious that in treating the material to be stretched by this device, that it would be impossible to tear the material, due to the fact that wherever the material comes in contact with the device, there are no sharp edges to tear or deface the material and that any one of these wedges may be used by springing them into the hinge element, as the construction of the hinge element permits flexibility, of the bosses 6 and 7, so that it will be very easy to place the wedges in this hinge element and when the wedges are

placed in the hinge element, the pivots will automatically line up the whole device.

Having thus illustrated and described the preferred embodiment of my invention, I do not wish to limit myself to the exact construction or arrangement of parts shown, since it is evident that modifications may be made therein, without departing from the spirit of the invention or scope of the claims.

20 I claim:—

1. A kyle comprised of a narrow, resilient V shaped hinge member, upwardly turned ears on the open ends of the hinge member, bearings on said ears, a detachable wedge, snapable into said hinge and fittable in spaced relation within said V shaped hinge member, an upwardly extending wedge shaped portion integral therewith, high at the wide end and low at the end opposite, an upwardly turned ear on said wide end and pivots on the said ear.

2. A kyle comprised of a narrow, resilient, V shaped hinge member, rounded inside edges thereupon, upwardly turned ears on the open ends, bearings in said ears, a detachable wedge springable into the bearings of the hinge ears, an ear on the wide end of said wedge, pivots on each side of said ear, said wedge fittable in spaced relation within the said V shaped hinge member, a double concave wedge portion integral with said wedge projecting upwardly and tapered toward the point of said wedge, the high point in spaced relation to said pivots and nail holes in said V shaped portion and wedge, said hinge coacting with the wedge pivots in resiliently positioning the wedge in the hinge member in cooperative relation.

Signed at New York, county of New York,
State of New York.
